FIG. 4.

FIG. 6.

INVENTOR

Colin Campbell Cooper

BY

Angerius B. Stoughton.

ATTORNEY.

WITNESS:

Prof. R. Kitchell.

UNITED STATES PATENT OFFICE.

COLIN CAMPBELL COOPER, OF NEW YORK, N. Y.

SHIRT.

1,263,743.

Specification of Letters Patent. Patented Apr. 23, 1918.

Application filed June 4, 1917. Serial No. 172,580.

To all whom it may concern:

Be it known that I, COLIN CAMPBELL COOPER, a citizen of the United States, and a resident of New York city, in the county 5 of New York and State of New York, have invented certain new and useful Improvements in Shirts, of which the following is a specification.

The principal objects of the present invention are, first, to provide shirts which present the attractive and desirable appearance of attached cuffs and which possess all the well known advantages of detachable cuffs, and second, to provide a neat, attractive and easily manipulated structure or arrangement of parts for detachably connecting wrist bands and cuffs in such a way that the detachable feature is concealed.

Other objects will appear from the following description taken in connection with the accompanying drawings, forming part hereof, and in which—

Figure 1, is a perspective view of a cuff showing a portion of the sleeve.

Fig. 2, is a face view of the outside of the cuff showing its flap in dotted lines.

Fig. 3, is a similar view showing a modification with the cuff turned back to expose the outside of the wrist band.

Fig. 4, is a similar view with the cuff slipped out of the pocket on the wrist band.

Fig. 5, is a perspective view showing the cuff about to enter the pocket, and

Fig. 6, is a sectional view.

The wrist band 1 is provided externally with a pocket *a*, closed at the edge 2 and ends 3 of the band and open along its other or inner edge 4. The cuff 5, is longer than

the band 1, and is provided at its inner edge 40 with a flap, shorter than the cuff, and adapted to be turned down to enter and extend the length of the pocket *a*.

The end parts 6 of the flap, and of the wall *b* of the pocket and of the cuff 5, are provided with alined stud—or button—holes. 7, is a tab that, if desired, may be provided at one edge of the cuff.

In use the cuff 5, is turned down (toward the left in Fig. 5) onto the flap 6 and the latter is slipped into the pocket *a*, and the

parts are secured in this position by studs 8, passed through the described button-holes. Ordinary sleeve buttons or links are passed through the button-holes 9, and the tab 7, if present, is buttoned over onto one of the 55 studs 8. An inspection of Fig. 1, shows that the joint between the cuff and sleeve is entirely inconspicuous not only in the center portion but also at the edges, and if visible upon close inspection gives the attractive effect or finish of a turned back cuff. The inside of the cuff presents an attractive appearance and looks not unlike an attached cuff.

I claim:

1. In a shirt the combination of a wrist band provided externally with a pocket closed at the outside edge and at the ends of the band and open along its inner edge, a cuff longer than and overlying and concealing the band and provided at its inner edge with a turned in flap shorter than the cuff and adapted to enter the pocket to give the effect of a turned back cuff, the flap and inner wall of the pocket and the cuff being 75 provided with alined stud holes, substantially as described.

2. In a shirt the combination of a wrist band provided externally with a pocket closed at the outside edge of the band and open along its inner edge, a cuff outside of and concealing the band and provided at its inner edge with a turned in flap adapted to enter the pocket and give the effect of a turned back cuff, the flap and the inner wall 85 of the pocket and the cuff being provided with alined stud holes, substantially as described.

3. In a shirt the combination of a wrist band provided externally with a pocket 90 closed at the outside edge and at the ends of the band and open along its inner edge, a cuff outside of the band and provided at its inner edge with a turned in flap adapted to enter the pocket and with a lateral tab 95 overlying the pocket, the flap and the inner wall of the pocket and the cuff being provided with alined stud holes, substantially as described.

COLIN CAMPBELL COOPER.
